(57) **CLAIM**

The ornamental design for a shampoo equipment, as shown and described.

DESCRIPTION

FIG. 1 is a front, left, top perspective view of a shampoo equipment, showing my new design;
FIG. 2 is a rear, right, bottom perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view of the shampoo equipment, shown at a reduced scale;
FIG. 8 is a bottom plan view of the shampoo equipment, shown at a reduced scale;
FIG. 9 is an enlarged view of a portion of the shampoo equipment shown within the area designated as 9 in FIG. 1;
FIG. 10 is an enlarged view of a portion of the shampoo equipment shown within the area designated as 10 in FIG. 1;
FIG. 11 is an enlarged view of a portion of the shampoo equipment shown within the area designated as 11 in FIG. 1;

FIG. 12 is an enlarged view of a portion of the shampoo equipment shown within the area designated as 12 in FIG. 2;

FIG. 13 is an enlarged view of a portion of the shampoo equipment shown within the area designated as 13 in FIG. 2; and,

FIG. 14 is an enlarged view of a portion of the shampoo equipment shown within the area designated as 14 in FIG. 3.

The dashed broken lines in the figures are for the purposes of illustrating portions of the shampoo equipment and form no part of the claimed design.

The dash-dot-dash broken lines are for notating enlarged views and form no part of the claimed design.

1 Claim, 11 Drawing Sheets
